AUTOMATIC TRAIN CONTROL

Paul J. Simmen, Eden, N. Y.

Application April 10, 1923, Serial No. 631,099

43 Claims. (Cl. 246—4)

This invention relates to railway train governing systems, particularly, those systems in which remote track switches are governed from a distant point, from which other train control apparatus is also governed, and relates more especially to systems specified in which there is both automatic and manual control and means for indicating or recording at a central station the movements of trains upon a trackway.

10 This invention relates to a system whereby an operator at a remote point is enabled to throw switches along the line of a railway and at the same time, display signals to the engineer of an approaching train indicating which position the switches are in, and, in general, operate the system with little, if any, recourse to the usual train order system of train dispatching.

15 Electrically operated switch machines for the purpose of throwing switches from a remote point are well known to those skilled in the art, but heretofore no system has been devised coacting with the switch mechanism by which the engineer is advised by means of distinctive signals, whether the switch is open or closed.

20 A further object of the invention is to prevent the throwing of a switch from a remote point when the train is too near the switch to enable it to be brought down to a reasonable speed, when the switch is open.

25 A further object of the invention is to indicate or record at a central station, as to what position the switch was in upon the approach of a train to it.

30 Other objects and advantages will appear as the description of the invention progresses and the novel features will be particularly pointed out in the appended claims.

In describing the invention in detail, reference is had to the accompanying drawing wherein I 35 have illustrated a preferred physical embodiment of my invention and wherein like characters of reference designate corresponding parts throughout the several views and in which:

40 Figure 1 is a schematic representation of the apparatus and circuits in the dispatcher's office, interlocking tower or way station, and along the track; Fig. 2, is a schematic representation of the apparatus and circuits on the locomotive or car by which, with certain cooperating parts of Fig. 1 signals are displayed on the locomotive or car.

45 Fig. 1 shows a main track consisting of track rails 1 and 2. Rail 1 is electrically continuous and rail 2 is divided into sections by means of insulating joints as 3, thus dividing the track into

block sections. Near one end of the block is a track battery as 4 and near the other end of the block are track relays as 5 and 6 constituting with their connections to the rails typical track circuits for the two blocks or sections of track, 60 well known to those skilled in the art. Track relay 5 is responsive to a train in block A and track relay 6 is responsive to a train in block B. In block B a siding as 7 is shown. At the clearance point of the siding, insulating joints as 3 65 electrically separate the straight portion of the siding from the main track. At the switch points of a switch as 159, leading into siding 7, is located a switch machine as S. The switch machine S may be of any well known type, consisting of a motor, which when current is supplied to it flowing in a certain direction, will close the switch, and if current is supplied to the motor flowing in the opposite direction the motor will rotate in the opposite direction and open the 75 switch.

70 For the purpose of brevity in this specification, by a "closed switch" is meant that a train moving from block A to B, will continue on the main track; and by an "open switch" is meant that the switch is in such a position that when a train 80 is moving from block A to block B, it will proceed into the siding.

75 Track relay 5 controls armatures 8 and 10 and when track relay 5 is energized, armature 10 85 will close front contact 11 and when track relay 5 is deenergized, armature 8 will close back contact 12. In Fig. 1, are shown four signals designated as No. 1, No. 2, No. 3 and No. 4. These signals are erected along the trackway in suitable locations in the usual manner so as to be easily visible to an engineer on an approaching train moving in the direction of the arrow in the trackway. While the four signals have been shown as grouped at one point, it is evident that 90 each signal may be located at any point along the track most suitable to be acted upon by the engineer of a train in approaching the switch.

95 These four signals are controlled by the several positions of the armatures of a relay 14, 100 suitably housed along the track. This relay is of the neutral-polar type, having both a neutral and polar armatures, and, as the armatures therefore may distinctively respond to three circuit conditions, is known as a three position relay. Through a manually operable pole changing switch 15 in the dispatcher's office, interlocking tower or way station, polarized relay 14 may be positively energized, or negatively energized or deenergized.

- When switch 15 is in contact with spring contact as 16, polarized relay 14 is positively energized through a circuit as follows: From positive pole of battery 17 in the dispatcher's office, wire 19, spring contact 16, switch 15, wire 20, relay 21, line wire 22, terminal 23, wire 24, terminal 25, resistance 26, polarized relay 14, wire 27, to track rail 1 and thence by wires 28 and 29 to the negative side of battery 17. 80
- When switch 15 is in contact with spring contact as 30, polarized relay 14 is negatively energized through a circuit as follows: From positive pole of battery 18 in the dispatcher's office, wires 31 and 28, to track rail 1 and thence by wire 27, polarized relay 14, resistance 26, terminal 25, wire 24, terminal 23, line wire 22, relay 21, wire 20, switch 15, spring contact 30, and wire 32, to the negative pole of battery 18. 85
- When switch 15 is disconnected from either spring contacts 16 or 30, no current is flowing through either of the two circuits described, and polarized relay 14 becomes deenergized. 90
- Polarized relay 14 controls a neutral armature 33, and four polarized armatures 34, 35, 36 and 37. Polarized armatures 34 and 35 are pole changing members of a switch for the purpose of changing the direction of flow of current in the circuit they control. Polarized armature 36 controls the circuit through signals No. 1 and No. 2; and polarized armature 37 is for the purpose of repeating certain signals on the locomotive as will be hereinafter more fully described. A commercial form of neutral polarized relay has a neutral armature carrying one or more contact fingers and a polarized armature carrying several contact fingers which are moved to establish or interrupt a circuit in accordance with the polarity of the relay magnet. These contact fingers, carried by the polarized armature, are herein referred to as polarized armatures. 100
- As hereinbefore stated when switch 15 is in contact with spring contact 16, polarized relay 14 is positively energized and neutral armature 33 makes contact with contact 38 and polarized armatures 34, 35 and 36 with contacts 39, 40 and 41, respectively. This position of the several armatures establishes a circuit through signal No. 1 as follows: From pole of battery 42, wires 43, 44 and 45, armature 33, front contact 38, wire 46, polarized armature 36, contact 41, wire 47, armature 9 of track relay 6, front contact 48, wire 49, signal No. 1, and wire 50, to the other pole of battery 42. 110
- A second circuit is also established through switch machine S as follows: From positive pole of battery 42, wires 43, and 51, contact 39, polarized armature 34, wire 52, motor of switch machine 53, wire 54, front contact 11, armature 10 of track relay 5, wire 55, polarized armature 35, contact 40, and wire 56, to the negative pole of battery 42. When the current is passing through motor 53 of the switch machine in the direction just described, the switch machine will close the switch. The circuit through motor 53 is taken through armature 10 of track relay 5, to prevent the dispatcher from throwing the switch while a train is occupying block A. It is obvious that when block A is occupied by a train, track relay 5 becomes deenergized, so that armature 10 will break front contact 11 and as long as the train remains in block A, the switch cannot be moved from the position it is in. 120
- Assume now that switch 15 is placed in the position to make contact with spring contact 16 by the dispatcher, thus displaying a clear signal to a train moving from block A toward block B and the signal No. 1 further indicating that the switch is closed; if there is a train in block B, then signal No. 1 is annulled by reason of track relay 6 being deenergized and armature 9 of track relay 6 breaking front contact 48 and thus breaking the circuit through signal No. 1. When block B is thus occupied, signal No. 1 is annulled by reason of track relay 6 being deenergized, a circuit is established through signal No. 4 as follows: from positive side of battery 42, wires 43 and 44 and 57, armature 13 of track relay 6, back contact 58, wire 59, signal No. 4, and wire 50, to the negative pole of battery 42. Thus when the dispatcher intends to display a clear or No. 1 signal to a train approaching block B, but there is a train in block B, signal No. 1 will invariably be annulled but signal No. 4 will be displayed indicating to the engineer that the block ahead is occupied. 130
- When switch 15 in the dispatcher's office is placed in contact with spring contact 30, polarized relay 14 is negatively energized as hereinbefore described, neutral armature 33 makes contact with front contact 38 but polarized armatures 34, 35, 36 and 37 are now in the left hand position opposite to that shown in Fig. 1 and they make contact with their respective contacts 60, 61, 62 and 63. This position of the several armatures establishes a circuit through signal No. 2 as follows: From positive pole of battery 42, wires 43, 44 and 45, armature 33, front contact 38, wire 46, polarized armature 36, contact 62, wire 64, signal No. 2 and wire 50 to the negative pole of battery 42. 140
- A second circuit is also established through motor switch machine S as follows: From positive pole of battery 42, wire 43, contact 61, polarized armature 35, wire 55, armature 10 of track relay 5, front contact 11, wire 54, motor 53, wire 52, polarized armature 34, contact 60, and wire 56 to the negative pole of battery 42. Thus when switch 15 is in contact with spring contact 30, switch machine S opens the switch since the direction of flow of current is now reversed through motor 53, and signal No. 2 is now displayed, indicating to the engineer to slow down, that the switch is open and to take the siding. It will be observed that while signal No. 2 may be displayed in this manner the switch machine cannot open the switch if block A is occupied for the same reason as hereinbefore described. 150
- When switch 15 is open so as to disconnect it from either spring contacts 16 and 30, polarized relay 14 is deenergized as hereinbefore described and neutral armature 33 makes contact with back contact 65. This position of the armature establishes a circuit through signal No. 3 as follows: From positive pole of battery 42, wires 43, 44 and 45, armature 33, back contact 65, wire 66, signal No. 3, and wire 50 to the negative pole of battery 42. Signal No. 3 may be used by the dispatcher to indicate to an engineer on an approaching train to stop and report to the dispatcher or it may be used for any other purpose as determined by the executive officers of the railway. 160
- It should be noted that relay 14 is what is known as a three position relay and is operated by a change in the characteristic of the current in its controlling circuit which change is effected in the dispatcher's office. Any three position relay, or equivalently functioning set of relays, having two energized positions and a deenergized position and operated by changing the characteristics of the energizing current can be sub- 170

stituted for relay 14. When a D. C., neutral-polar relay is used, when deenergized the contacts controlled by the polarized armatures usually remain in the position they last occupied during the preceding energized condition of the relay.

The circuit described and illustrated for the power operated switch movement includes only the part of the circuit for reversing the direction of current to the switch mechanism to cause an operation of the switch, and for control of the switch mechanism by the track relay. In practice, the motor may be energized through any suitable circuits and the reversing action controlled by the circuit illustrated. The actual wiring of the switch motor forms no part of the present invention, and since its control by the mechanism is usually embodied in the mechanism itself and is well understood in commercial machines for this purpose, it is not included herein.

I will now describe the mechanism in the dispatcher's office by which the arrival of a train at a switch is recorded and whether the switch was in a closed or in an open position.

In the dispatcher's office, interlocking tower, or way station is a suitably mounted record sheet as 67, driven by a roller as 68, which in turn is driven by a shaft as 69. Shaft 69 receives motion through a ratchet wheel as 70. A pawl 71 is pivotally connected to armature 72 of electro-magnet as 73. Armature 72 is hinged at 74. When electro-magnet 73 is periodically energized, motion is given to the ratchet wheel 70 through pawl 71. A spring as 75, normally pulls armature 72 and pawl 71 to the right, when electro-magnet 73 is not energized. Electro-magnet 73 is connected by a wire 76 to a make-and-break device 77, which make-and-break device 77 is operated by a clock as 78. This may well be of a form shown in my prior Patent No. 1,203,146 granted October 31, 1916. When the make-and-break device is closed the electro-magnet 73 is energized through the following circuit: From battery 79, wires 80, and 81, electro-magnet 73, wire 76, make-and-break device 77, wires 82 and 83 to the other pole of battery 79. The make-and-break device 77 is operated say every five seconds, by the clock 78 so as to give a slow and uniform movement to the record sheet 67 through ratchet wheel 70 and pawl 71.

Longitudinally the record sheet is divided into time lines such as 1.00 A.M. each one of the lines representing a one minute interval. Since the make-and-break device continues to be operated in an intermittent manner it will be seen that longitudinally the record sheet assumes a progressively changing position during the 24 hours of the day.

Adjacent to the record sheet are located perforating magnets as 84 and 85 controlling armatures as 86. Pivotally attached to armatures 86 are perforating needles as 87 so positioned adjacent to the record sheet that when a perforating magnet is energized, a perforation is made in the record sheet.

Attached to switch 15 but insulated therefrom are metallic wedges as 88 and 89 so positioned that when switch 15 is placed in contact with spring contact 16, metallic wedge 88 will make contact with contact springs as 90 and 91 thus electrically connecting the two contact springs and when switch 15 is placed in contact with spring contact 30, metallic wedge 89 will electrically connect springs 92 and 93.

When switch 15 is in contact with spring con-

tact 16, current is flowing through relay 21 in the dispatcher's office but this current is not of sufficient strength to attract armature 94 of relay 21 so as to close front contact 95 for the reason that as long as block A is not occupied, the current is passing through resistance 26. As soon however, as a train enters block A, track relay 5 becomes deenergized and a shunt circuit is established around resistance 26 as follows: From terminal 23 in the main circuit, wire 96, armature 8 of track relay 5, and back contact 12 to wire 27. In this manner the current passing through relay 21 is increased sufficiently to cause it to attract armature 94 and close front contact 95 and a circuit is closed through perforating magnet 84 as follows: From battery 79, wires 80 and 97, metallic plate 98, wires 99 and 100, perforating magnet 84, wire 101, contact spring 90, metallic wedge 88, contact spring 91, wires 102 and 103, front contact 95, armature 94, and wire 83 to the opposite pole of battery 79.

The circuits through both perforating magnets 84 and 85 are taken through a circuit breaking device 98 so that this circuit is periodically made and broken. This circuit breaking device operates as follows: Metallic contact plate 98 is attached to armature 72 and insulated therefrom. Every time the electro-magnet 73 is energized which as hereinbefore stated is say every five seconds, the circuit through wires 97 and 99 is closed, through metallic plate 98. When magnet 73 is deenergized armature 72, is pulled to the right by spring 75 and the circuit through wire 97 and 99 is broken. By reason of this periodic breaking of the circuit through the perforating magnet, an intermittently continuous perforation is made on the record sheet as long as block A is occupied.

Assuming now that switch 15 is in contact with spring contact 30 thus connecting contact springs 92 and 93, current is flowing through relay 21 in the dispatcher's office but this current is not of sufficient strength to attract armature 94 and close front contact 95 as hereinbefore described. As soon however as a train enters block A, this shunt circuit through armature 8 of track relay 5 is established and then there is sufficient current flowing through relay 21 to attract armature 94 and close front contact 95 and when this occurs a circuit is closed through perforating magnet 85 as follows: From battery 79, wires 80 and 97, metallic contact plate 98, wires 99 and 104, perforating magnet 85, wire 105, contact spring 92, metallic wedge 89, contact spring 93, wire 103, front contact 95, armature 94, and wire 83 to the other pole of battery 79.

It will thus be seen that when switch 15 is in contact with spring contact 16, thus indicating to the engineer by signal No. 1, that the switch ahead is closed, perforating magnet 84 will perforate the record sheet as soon as a train enters block A, and when switch 15 is in contact with spring contact 30, thus indicating to the engineer by signal No. 2 that the switch ahead is open, perforating magnet 85 will perforate the record sheet, as soon as a train enters block A. Furthermore the selected perforating magnet will record the exact time when a train entered block A and will continue to perforate until the train has left the block, thus recording the length of time the train remained in the block.

The record sheet 67 not only makes a permanent record of the train and the time when it passed through section A, but the sheet itself is a visual indicator of these conditions. In addi-

tion to this, a distinctively different record and indication is made of a train that is signaled for the siding from a train running on the main line, and the dispatcher can gage the speed of these 5 trains by noting the length of time they occupy section A. This system of transferring information from the trackside to the dispatcher's office is officially known as OS-ing.

It will be understood that the indicating and 10 recording apparatus is controlled by the translating relay 21, and that hereinafter and in the appended claims the term "translating" relay or device will be understood to include such device when used for recording or indicating purposes, 15 or both.

The centralized traffic control system as described operates on one line circuit to control the trackside apparatus, including signals and track switch, and to indicate and record at the central 20 office certain conditions existing or taking place on the trackway. In the diagrammatic illustration one of the line wires, the return conductor from wire 27 to wire 28 connecting batteries 17, 18, has been eliminated by utilizing one of the 25 running rails of the track as a return conductor. This arrangement is satisfactory and may be used instead of a return line wire when a track rail that is properly bonded at the rail joints can be given over to this purpose.

30 For the purposes of indicating and recording at the central office over the line circuit, it will be understood that the translating relay 21, connected with relay 14 in the controlling circuit, is of such construction that it will not lift its 35 armature when the current in the line is small as when the resistance is high, but will lift its armature when the current flow is great. The resistance is lowered to render the current flow great by shunting a resistance in the circuit, such as resistance 26, by the track relay 5 dropping its armature 8.

It will be noted that in the diagrammatic illustration this resistance 26 is included in series with relay 14, both the resistance and relay 14 being shunted by back contact 8 of relay 5. When relay 14 is thus included with resistance 26 in the shunted circuit, rather than including the resistance 26 alone in the shunted circuit, it will be understood that the resistance values of 40 the shunt circuit 96, 8, 12 and the shunted circuit are such as to insure current passage through relay 14 sufficient to maintain this relay with its armature in picked-up position at all times when the control circuit is energized.

55 I will now describe how signals No. 1, 2, and 3 along the track may be reproduced on the locomotive. In Fig. 1 are located train control rails 106 and 107 along the track, train control rails 106 being positioned near the beginning of the 60 block or section A and train control rail 107 being located approximately braking distance from the entrance to the block B. These train control rails may be positively energized, negatively energized or deenergized, similarly to and in correspondence with polarized relay 14. The circuit through the dispatcher's office by which the different electrical conditions are established in the train control rails are similar to those described for polarized relay 14 and are as follows:

65 When the train control rails are positively energized, it is by a circuit established from positive pole of battery 17, wire 19, spring contact 16, switch 15, wire 20, relay 21, line wire 22, terminal 23, wire 96, wire 108, armature 111, front contact 109 of track relay 6, wire 110, to train

control rails 106 and 107 and thence through a circuit on the locomotive to be described hereinafter to track rail 1 and thence through wires 28 and 29 to the negative pole of battery 17.

When the train control rails are negatively energized, the circuit through the dispatcher's office is as follows: From positive pole of battery 18, wires 31 and 28 to track rail 1 and thence through a circuit on the locomotive to be described hereinafter to train control rails 106 and 107 and thence through wire 110, front contact 109, armature 111, of track relay 6, wires 108 and 96, terminal 23, line wire 22, relay 21, wire 20, switch 15, spring contact 30 and wire 32 to the negative pole of battery 18. It will be noted that this circuit is taken through front contact 109 of track relay 6 and when there is a train in block B, this circuit which normally energizes the train control rails is broken but a branch circuit is established, which will negatively energize train control rails irrespective of whether there is a train in block B or not as follows: From terminal as 100 112, in wire 110, wire 113, contact 63, polarized armature 37, of polarized relay 14, and wire 114, terminal 25, and wire 24, to terminal 23 in the new circuit.

When switch 15 is disconnected from both 105 spring contacts 16 and 30, no energy can reach train control rails 106 and 107 and therefore these rails are deenergized.

In Fig. 2 are shown three signals or instrumentalities on the locomotive as No. 5, 6 and 7. Signal No. 5 is displayed when a locomotive is 110 passing a train control rail which is positively energized. Signal No. 6 is displayed when a locomotive is passing a train control rail which is negatively energized and signal No. 7 is displayed when a locomotive is passing a train control rail which is deenergized, as will be described more fully hereinafter.

115 It will thus be seen that when switch 15 is in contact with contact spring 16, polarized relay 14 is positively energized, thus displaying signal No. 1 along the track and closing the track switch and train control rails are also positively energized 120 and signal No. 5 is displayed on the locomotive when it passes a train control rail. If, however, there is a train in block B, track relay 6 becomes deenergized and signal No. 4 will be displayed along the track and the train control rails will also 125 be deenergized by reason of armature 111 of track relay 6 breaking front contact 109 and under these conditions signal No. 7 will be displayed. When switch 15 is in contact with contact spring 30, polarized relay 14 is negatively energized thus 130 displaying signal No. 2 along the track and opening the track switch and the train control rails are also negatively energized and signal No. 6 is displayed on the locomotive, when it passes the 135 train control rail, thus indicating that the track switch is open. Both signal No. 2 and signal No. 6 are displayed irrespective of whether there is a train in block B or not. When switch 15 is disconnected from either contact spring 16 or 30 polarized relay 14 is deenergized, thus displaying signal No. 3 along the track and train control rails are also deenergized thus displaying signal No. 7 on the locomotive.

145 The cab circuits capable of displaying three different signals corresponding to the three different electrical conditions of the train control rails are shown in Fig. 2 and are similar to those circuits shown in my prior Patent No. 1,239,049, granted September 4, 1917.

While the instrumentalities No. 5, 6 and 7 in Fig. 2 are shown as lamps, they may equally represent an electro-magnetic device to which motion is given depending upon whether the circuit is energized or deenergized and such electro-magnetic device may be used for other purposes than, or in addition to, the display of signals to the engineer, such as the proper control of speed control devices or electro-pneumatic air valves 10 or both.

In Fig. 2 is shown an electric contact shoe 115, so positioned on the locomotive as to make contact with train control rails 106 and 107. The contact shoe is hinged as at 116. Train control rails 106 and 107 are inclined at the ends so as to form a ramp in the usual manner as shown in my prior Patent No. 1,140,623, granted May 25, 1915, and when the contact shoe slides along the ramp, the shoe is tilted so as to break contact 117. This motion of the shoe compresses a spring as 118. When the contact shoe leaves the other end of the train control rail, spring 118 forces the contact shoe to the normal position making contact with contact 117. The locomotive also carries a polarized relay as 119 and a battery as 120. The polarized relay 119 controls a neutral armature as 121 and four polarized armatures 122, 123, 124 and 125. Polarized armatures 123 and 124 are pole changing members of a switch for the purpose of changing the polarity of current from battery 120. Polarized armature 125 controls by its position signal No. 5. Polarized armature 122, controls by its position signal No. 6 and neutral armature 121 controls by its position signal No. 7. Depending upon the direction of the flow of current in relay 119, polarized armature 122, 123, 124 and 125 will assume either one or the other of their two positions, to the left as shown or to the right.

When the contact shoe 115 is passing a train control rail which is positively energized, an electrical circuit is established as follows: From train control rail 106, contact shoe 115, wire 126, polarized relay 119, wire 127, 128 and 129, resistance 130, wire 131, axle 132, wheel 133, to track rail 1 and thence the circuit is completed through battery 17 in the dispatcher's office as hereinbefore described. Under these conditions polarized relay 119 will be positively energized but neutral armature 121 will make contact with front contacts as 134 and 135, and polarized armatures 122, 123, 124 and 125 will assume the left hand position as shown in Fig. 2 and will make contact with their respective contacts as 136, 137 and 138. In this position of the several armatures, a circuit is established through signal No. 5 as follows: From positive pole of battery 120, wire 147, contact 138, polarized armature 123, wire 146, armature 121, front contact 135, wire 145, polarized armature 125, contact 136, wire 144, signal No. 5, wires 143, 142, 128 and 141, polarized armature 124, contact 137, wires 140, and 139 to the negative pole of battery 120.

When the shoe 115 leaves the other end of the thus positively energized train control rail, contact 117 is again made and a stick circuit is established through polarized relay 119 which maintains the armatures of the relay in the same position as follows: From positive side of battery 120, wire 147, contact 138, polarized armature 123, wire 146, armature 121, front contact 134, wire 148, contact 117, contact shoe 115, wire 126, polarized relay 119, wires 127, and 141, polarized armature 124, contact 137, and wires 140 and 139 to negative pole of battery 120. Thus the

signal indication obtained at a train control rail is continued until the next train control rail is reached.

When the contact shoe 115 makes contact with a train control rail which is negatively energized, an electrical circuit is established from track rail 1, wheel 133, axle 132, wire 131, resistance 130, wires 129, 128 and 127, polarized relay 119, wire 126, contact shoe 115, to contact rail 106 and thence the circuit is completed through battery 18 in the dispatcher's office as hereinbefore described. Under the conditions of current flow, polarized relay 119 will be negatively energized, neutral armature 131 will still make contact with front contacts 134 and 135 but the polarized armatures 122, 123, 124 and 125 will now assume the right hand position opposite to the one as shown in Fig. 2 thus making contact with their respective contacts 151, 150 and 149. In this position of the several armatures a circuit is closed through signal No. 6 as follows: From positive pole of battery 120, wire 147, contact 149, polarized armature 124, wires 141, 128, 142 and 152, signal No. 6, wire 153, contact 151, polarized armature 122, wires 154 and 145, front contact 135, armature 121, wire 146, polarized armature 123, contact 150, and wires 155, and 139 to the negative pole of battery 120.

When the shoe 115, leaves the other end of the negatively energized train control rail, contact 117 will again be closed and a stick circuit is established through polarized relay 119 thus maintaining the armatures in the same position as follows: From positive pole of battery 120, wire 147, contact 149, polarized armature 124, wires 141 and 127, polarized relay 119, wire 126, contact 115, contact 117, wire 148, front contact 134, armature 121, wire 146, polarized armature 123, contact 150, and wires 155 and 139 to the negative side of battery 120.

When shoe 115 contacts with a train control rail which is deenergized, signal No. 7 is established on the locomotive in the following manner: When shoe 115 moves along the ramp portion of the train control rail, contact 117 is opened and thus the stick circuit which normally maintains polarized relay 119 energized between the train control rails, is broken. Under these conditions neutral armature 121 drops and makes contact with back contact 156, thus establishing a circuit through signal No. 7 as follows: From positive pole of battery 120, wire 147, contact 138, polarized armature 123, wire 146, armature 121, back contact 156, wire 157, signal No. 7, wires 158, 142, 128 and 141, polarized armature 124, contact 137, and wires 140 and 139 to the negative pole of battery 120.

When the contact shoe leaves the other end of the deenergized train control rail, contact 117 is again closed but the normal stick circuit for relay 119 is not reestablished since this circuit is now open at front contact 134. Thus signal No. 7 is continued until an energized train control rail is reached. It will thus be seen that a switch may be opened or closed from a remote point such as a dispatcher's office, interlocking tower or way station and display corresponding signals along the track and the signals duplicated on the locomotive and, further a record may be made at the control point as to whether the switch was open or closed when a train approaches a switch. At the same time a track switch may not be moved from one position to another if a train is so close to a switch that it would be unable to reduce speed from a maximum speed to the necessary

lower speed in order to take the switch at the siding safely.

It will be noted that the shoe 116 is applied on one side of the vehicle only and that the ramp rails 106, 107 are located on one side of the track only and that the control is for traffic going in the direction of the arrow. Thus the drawing shows the application of the system for traffic in one direction only and when the train is moving in the opposite direction, with the locomotive turned around, shoe 116 is then on the opposite side of the track and away from the influence of ramps 106, 107. If the system is to be applied to control traffic in both directions additional ramps and track circuits would be required. The drawing is intended to illustrate the fundamentals of the system and is not intended to take the place of a block system for traffic in one or both directions but is intended to be embodied therein.

In the dispatcher system of controlling traffic to which this invention belongs, there is usually other methods of advising the dispatcher of train movements than the OS-ing system disclosed herein. For instance, the dispatcher knows from his train sheet and time table when a train is due at a passing siding and he can set up the main line switch and the corresponding signal for a through movement, or he can set the switch and signal for the siding before the train arrives on section A. When the train is on section A the dispatcher cannot then control the movement of the switch by his controller but he can control the indication of the wayside signals and the cab signals. If the switch is to be changed with a train on section A this can be done by the train crew after the train has been brought to a stop and the dispatcher can deenergize the ramp rails for this purpose.

The dispatcher thus has selective control over the switches and the signals but his control over the switch is suspended by a train on a certain portion of the track.

After the ramp rails have been deenergized by a train in section B to cause the train to stop, the dispatcher can exercise his control to give a slow speed signal to the vehicle by energizing the ramp rails negatively. As the dispatcher has before him a record of the time the train has occupied section A he can gage its speed and, if desired, permit it by a slow speed signal to close up on a train in section B. The pair of spaced ramps in section A enables the dispatcher to exercise his control of the cab signals twice in this section. He may institute a low speed signal at the first ramp and stop at the second or he can reverse these conditions.

The ramps 106, 107, as shown in the diagram are energized from the line circuit on wire 22 and with a train in section A, the wire 22 is shunted by the back contact of relay 5 to the return rail; this shunt, however, does not short circuit the ramp rails, but leaves them sufficiently energized to effectively energize the relay 119 on the locomotive. The cab signal apparatus is operated by one polar-neutral relay with one battery, the polarity of the current from which is controlled by this relay. When the relay is energized its holding or stick circuit is energized by the local battery in the direction which holds the polar armature in the position established at the time it was energized.

The ramp and shoe system of train control is used as a convenient method of showing the application of my invention in the locomotive cab.

The application may be used with other systems of train control in which the ramps correspond with controlled trackway apparatus to which the vehicle apparatus is responsive.

Although I have particularly described one preferred physical embodiment of my invention and illustrated the same, nevertheless I desire to have it understood that the particular form illustrated is merely illustrative, and does not exhaust the possible physical embodiments of means underlying the principles of my invention.

The invention includes a full range of equivalents for the apparatus illustrated of which a variety are commercially obtainable. Where the specification expresses a theory of operation it is in accord with the operation as at present understood but may be subject to modifications in the light of later knowledge.

What I claim as new and desire to secure by Letters Patent of the United States, is:—

1. In a railway train control system, in combination: a trackway; means dividing the trackway into electrically isolated sections; siding switches at intervals along the trackway; motors for operating said switches; a car; controlling instrumentalities on the car; a central station; a recording mechanism at the central station; means at the central station and operatively connecting the central station, car and switch motors, and said recording mechanism, whereby when the motors are operated the car instrumentalities are operated and records are made at the central station of the movements of the car.

2. In a railway train control system, in combination: a trackway; means dividing the trackway into electrically isolated sections; siding switches at intervals along the trackway; motors for operating said switches; a wayside signal for each switch adapted to indicate the closed position thereof; a wayside signal for each switch adapted to indicate the open position thereof; a central station; means at the central station for simultaneously operating the switch and one of the signals and for selecting the signal which corresponds to the position of the switch as effected by the operation of said means; a vehicle, a cab signal on the vehicle having a plurality of indications; and means for changing the cab signal indications by said means at the central station.

3. In a railway train control system, in combination: a trackway having track circuits with track relays; siding switches at intervals along the trackway; motors for operating said switches and controlled by said track relays; a signal for each switch adapted to indicate the closed position thereof; a signal for each switch adapted to indicate the open position thereof; a central station; means at the central station for simultaneously operating the switch and one of the signals and for selecting the signal which is adapted to indicate the position of the switch as effected by the operation of said means; and means at the central station controlled by said central station means and also controlled by said track relays for recording the presence of the car on the track circuits.

4. In a railway train control system in combination, a trackway divided into blocks, a siding switch diverging from the main trackway, a motor for operating said switch to the open or closed position, signals to indicate the condition of the trackway, a relay adjacent the trackway for controlling the motor and the signals, a central office, one electrical circuit between said central office and said relay, and manually operated means at

the central office for conditioning said circuit to effect operation of said switch motor and said signals.

5. In a railway train control system in combination, a trackway divided into blocks, a siding switch diverging from the main trackway, a motor for operating said switch to the open or closed position, signals to indicate the condition of the trackway, a relay adjacent the trackway for controlling the motor and the signals, a central office, one electrical circuit between said central office and said relay, and manually operated means at the central office for conditioning said circuit to effect the operation of said switch motor and said signals, and track circuit means for rendering the manual conditioning of the motor for operating the siding switch ineffective if a train is in a block adjacent the siding switch.

6. In a railway train control system in combination; a trackway; a train; a siding switch diverging from the main trackway; a motor for operating said switch to the open or closed position; signals to indicate the condition of the trackway; means adjacent the trackway for controlling the motor and the signals; a central office; one electrical circuit between said central office and said means adjacent the trackway; manually operated means at the central office for controlling said means adjacent the trackway, by conditioning said electrical circuit, to effect operation of said switch motor and said signals; a track circuit on said trackway having a track relay controlling said switch motor; and means controlled by said track relay to indicate through said electrical circuit the entrance of said train upon the track circuit.

7. In a railway train control system in combination, a trackway; a train; a siding switch diverging from the main trackway; a motor for operating said switch to the open or closed position; signals to indicate the condition of the trackway; a relay adjacent the trackway for controlling the motor and the signals; a central office; one electrical circuit between said central office and said relay; manually operated means at the central office including a source of current for conditioning said relay through said circuit to operate said switch motor and said signals; a track circuit on said trackway having a track relay controlling said switch motor; and means controlled by said track relay to indicate through said electrical circuit the entrance of a train upon the track circuit and the kind of signal, to be displayed to the train, for which said relay was conditioned at the time of entrance.

8. In a railway train control system in combination, a trackway divided into blocks, a siding switch diverging from the main trackway, a motor for operating said switch to the open or closed position, three signals, one to indicate proceed along the main trackway, one to indicate proceed into the siding, and one to indicate stop, a source of current for operating said motor and said signals, a relay adjacent the trackway for controlling the motor and the signals, a central office, one electrical circuit between said central office and said relay, manually operated means at the central office including a source of current for conditioning said switch motor and said signals to effect the operation thereof, a track circuit for each block, and means controlled by said track circuits by which the manual conditioning of the proceed signal and the motor for operating the siding switch become ineffective if a train is in the

block adjacent the siding switch, and means located at the said central office, rendered operable by one of said track circuits, to indicate the entrance of said train into the block and the kind of signal displayed to the train.

9. In a railway train control system in combination, a trackway divided into blocks, a siding switch diverging from the main trackway, a motor for operating said switch to the open or closed position, three signals, one to indicate proceed along the main trackway, one to indicate proceed into the siding, and one to indicate stop, a source of current for operating said motor and said signals, a relay adjacent the trackway for controlling the motor and the signals, a central office, one electrical circuit between said central office and said relay, manually operated means at the central office including a source of current for conditioning said switch motor and said signals to effect the operation thereof, a track circuit for each block, and means controlled by said track circuits by which the manual conditioning of the proceed signal and the motor for operating the siding switch become ineffective if a train is in the block adjacent the siding switch, and an indication is given at said central office, over said electrical circuit, of the entrance of said train into the block and the kind of signal displayed to the train.

10. A train dispatching system comprising, a main track and a siding diverging therefrom, a track switch for controlling movement of traffic over the main track and into said siding, signals for governing movement of traffic over said main track and into said siding, a switch machine for governing operation of said track switch, a distant dispatcher's office, an indicator in said dispatcher's office, a lever in said dispatcher's office, and means for controlling said indicator by a train approaching said switch and controlling said switch machine and signals in accordance with the operated position of said lever over the same line circuit.

11. In a train OS-ing system, the combination with a railway track having a portion thereof divided from the rest of said track by insulating joints, a track circuit for said portion including the usual normally energized track relay and a source of current, a dispatcher's office, a line circuit connecting said office and said track portion including indicating means located at said office, a wayside signal located at said track portion governed in accordance with traffic conditions on said track portion and in advance thereof, and means for causing said indicator to distinctly respond to the condition of said track relay and the indicating condition of said wayside signal.

12. Means for operating an outlying track switch and indicating the movement of a train over said switch comprising, a switch machine for operating said track switch, a polar control relay located near said switch machine which if energized to one energized position operates said switch machine and in turn the track switch to one extreme position and if energized to the other position operates said track switch to the other extreme position, a line circuit connecting a local train dispatcher's office and said polar control relay, an indicator at the office end of said line circuit, a lever in said office for energizing said polar control relay and in turn operating said switch machine, and means for controlling the indicating condition of said indicator.

- cator over said line circuit in accordance with the passage of a train by said track switch.
13. A method of dispatching the movement of trains by visual signal indications visible to the engineer of approaching trains on railway systems of which the track is provided with spaced sidings each having a track switch operable by a power operated switch machine, and having a track circuited fouling section, and a track circuited approach section; which consists in giving a train dispatcher located at a point distant from said siding supervisory control over such switch machine for a particular siding end, and in depriving the train dispatcher of such supervisory control over the switch machine during the approach of a train in the approach section without depriving the train dispatcher of such supervisory control over one of such visual signals.
14. In a non-train-order train dispatching system, the combination with an outlying siding, a track switch for said siding, a switch machine for operating said track switch, signals governing the movement of trains by said track switch, and unitary supervisory control means for controlling both said signals and said switch machine, said supervisory control means being so constructed and interconnected with said switch machine that the approach of a train to the switch will prevent operation of said switch machine through the medium of said supervisory control means, and means for informing the dispatcher as to the progress of such train along the track.
15. In combination, a section of railway track, two devices for governing traffic through said stretch, manually controlled means for placing one device in a predetermined condition, manually controlled mechanism for operating the other device, control instrumentalities at a dispatcher's office for said manually controlled means and mechanism, and means set into operation when a train approaches said section for rendering said mechanism ineffective to operate said other device without disabling said manually controlled means for said one device.
16. In a non-train-order train dispatching system; the combination with a railway main track having a side track diverging therefrom; a railway vehicle; cab signals in the cab of said railway vehicle including two signal indications; and means for governing the indicating conditions of said signals by said dispatching system and in accordance with traffic conditions and route conditions in advance; whereby one signal indication is displayed in the cab if the vehicle is not to pass the switch on the main track nor enter the side track, and a second indication is displayed when the route is set up over said side track.
17. A non-train-order cab signal train dispatching system for railways having passing sidings comprising; a railway vehicle having a diverging route signal in the cab thereof; a railway track having a diverging route, and a track switch for directing traffic into the straight track or into said diverging route; a switch machine for operating said track switch; means for controlling said switch machine from a distant point; means for displaying the diverging route cab signal upon the approach of the vehicle to the track switch if the track switch is set for the diverging route, and other cab signal means for indicating the condition of track occupancy ahead.
18. In combination, a railway traffic govern-
- ing device, a first relay for controlling said device, an indication relay, a circuit including said first relay and said indication relay in series, and means responsive to a train on the track operating upon said circuit to effect the operation of said indication relay but not the operation of said first relay.
19. A non-train-order train dispatching system for single track railways comprising a manually operable circuit controller, a relay located at a siding distant from said controller, a circuit connecting said controller and relay, a recording device in said circuit at the controller end of said circuit, a source of energy at the circuit controller end of said circuit which through said circuit controller may be applied to said relay and said recording device, and means at the relay end of said circuit for effecting operation of said recording device without affecting the operation of said relay.
20. In a non-train-order train dispatching system, the combination with a control relay located at a distant siding, signals located at such siding controlled jointly by a track relay at such siding and said control relay, a circuit for said control relay including control means and a recorder, and means for operating said recorder over said circuit without interfering with the control of said control relay by said control means.
21. In a non-train-order train dispatching system, the combination with a railway track having a side track diverging therefrom, a railway vehicle, cab signals in the cab of said railway vehicle having at least three signal indications, and means controlled from the dispatcher's office for governing the indicating conditions of said cab signals in accordance with traffic conditions and route conditions in advance of the vehicle, whereby the engineer is distinctively informed by indications in the cab as to whether he is to take the side track or the main track upon his approach to said side track.
22. In a non-train-order train dispatching system, the combination with a railway track having a side track diverging therefrom, a railway vehicle, cab signals in the cab of said railway vehicle having at least three signal indications, a track switch at the entrance to said side track, and means controlled from the dispatcher's office for governing the indications of said cab signals in accordance with traffic conditions ahead and in accordance with the position of said track switch upon the approach of said vehicle toward the points of said switch.
23. A non-train-order cab signal train dispatching system for railways having passing sidings comprising; a railway vehicle having a three indication cab signal; means partly on the vehicle and partly along the trackway for governing said signal indications in accordance with traffic conditions ahead of the vehicle and in accordance with manually operable means located at a distant tower.
24. In a train dispatching system, a single track and an adjoining main track having a siding to permit the passage of trains; a plurality of signals located at the entrance of the siding for governing the movement of trains either into the siding or the main track; manually controlled means located at a central office for controlling said signals; a source of current; a single circuit extending from said central office and including said source of current, the manual means for controlling said signals and a track circuit in said single track; and means located

- at the central office responsive to said track circuit for recording electrically the time of entrance of a train into and departure of a train from the single track.
- 5 25. A non-train-order train dispatching and O.S. signaling system for railways comprising, a manually operable circuit controller, a relay located at a siding distant from said controller, a circuit connecting said controller and relay, 80
10 an indicating device in said circuit at the controller end of said circuit, a source of energy at the circuit controller end of said circuit which through said circuit controller may be applied to said relay and said indicating device, and 85
15 means at the relay end of said circuit for operating said indicating device without affecting normal operation of said relay.
26. A method of dispatching the movement of trains over railway systems having power operated track switches at the ends of sidings, and signals at such track switches for governing the direction of train travel over said track switches; which consists in giving the train dispatcher selective supervisory control over the signals and 90
25 control over the switch machines, in taking away such supervisory control as far as it affects the control of the switch machine but not taking it away as far as it affects the control of the signals when there is a train approaching said track switch.
27. A method of dispatching the movement of trains over railway systems having power operated track switches at the ends of siding, and signals at such track switches; which consists in giving 95
35 the train dispatcher supervisory control over the signals and the switch machines, in taking away such supervisory control as far as it affects the control of the switch machine but not taking it away as far as it affects the control of the signals when there is a train approaching said switch machines, said supervisory control being capable of controlling said signals only to give indications the same as or more restrictive than the actual traffic conditions existing in advance of 100
45 such signals.
28. A switch and signal system for controlling the movement of trains into the side track or main track of a siding located at a distant point, a track switch for determining whether an approaching train shall enter the side track or main track, a switch machine for operating said track switch, a track circuit controlling said switch machine, signals at said track switch for governing the movement of trains into said side track and main track, a relay controlled from a local lever for controlling said switch machine and signals, and means for preventing operation of such switch machine in response to operation of said relay if an approaching train has entered 115
50 upon said track circuit, but permitting operation of said signals.
29. A method of dispatching the movement of trains by visual signal indications on a railway system of which the track is provided with spaced 120
55 sidings each having a track switch operable by a power operated switch machine, a track circuited approach section at the approach of said siding, a single circuit connecting said siding with a train dispatcher's office; which method consists in giving the train dispatcher supervisory control over said signals and over the switch machine through the medium of said circuit, in informing the train dispatcher as to the movement of trains through the medium of said circuit, and 125
60 in depriving the train dispatcher of said supervisory control as to the switch machine but not as to the signals when there is a train approaching said track switch.
30. In a non-train-order train dispatching and signalling system; the combination with a railway track having an outlying passing siding; a track switch at the entrance end of said siding; a signal for governing the entrance of trains to the main track of said passing siding; a signal for governing the entrance of trains to the siding of said passing siding; a three position control relay which if in one energized position permits one of said signals to clear subject to control of conditions of traffic ahead, which if in the other energized position permits the other signal to clear, and which if in the deenergized condition permits neither of said signals to clear; a line circuit for controlling said control relay from the train dispatcher's office; and means including said line circuit to inform the train dispatcher as to the passage of trains by said track switch.
31. A train dispatching system comprising, a main track and a siding diverging therefrom, a track switch for controlling movement of traffic over the main track and into said siding, signals 130
100 for governing movement of traffic over said main track and into said siding, a switch machine for governing operation of said track switch, a track circuit in the stretch of track approaching said track switch, a distant dispatcher's office, an indicator in said dispatcher's office, a lever in said dispatcher's office, and means for controlling said indicator in accordance with the occupancy of said track circuit and controlling said switch machine and signals in accordance with the operated position of said lever over the same line circuit.
32. A railway traffic controlling system comprising a main track and a connecting track, a power operated switch movement operating the switch to the connecting track, a signal, a track circuit with a track relay, a three position relay selectively controlling both operations of said switch movement and the indication of said signal, said track relay controlling said switch movement, a dispatcher's office with a controlling switch, a circuit connecting said three position relay with said controlling switch for the selective operation of said three position relay, and a translating device connected in said circuit 135
115 at the dispatcher's office.
33. A railway traffic controlling system comprising a main track and a connecting track, a power operated switch movement operating the switch to the connecting track, a signal, a track circuit with a track relay, a three position relay selectively controlling said switch movement and said signal, a dispatcher's office with a controlling switch, a circuit connecting said three position relay with said controlling switch for the selective operation of said three position relay, and a translating device at the dispatcher's office connected in said circuit and means for operating said translating device by said track relay.
34. A railway traffic controlling system comprising a main track and a connecting track, a power operated switch movement operating the switch to the connecting track, a signal, a track circuit with a track relay, a three position relay 140
145 selectively controlling said switch movement and said signal, said track relay controlling said switch movement, a dispatcher's office with a controlling switch, a circuit connecting said three position relay with said controlling switch for the selective

- operation of said three position relay, and a translating device at the dispatcher's office connected in said circuit and brought into operation by the operation of said track relay.
35. A railway traffic controlling system comprising a main track and a connecting track, a power operating switch movement operating the switch to the connecting track, a signal, a track circuit with a track relay, a three position relay selectively controlling said switch movement and said signal, a dispatcher's office with a controlling switch, a circuit connecting said three position relay with said controlling switch for the selective operation of said three position relay, and a translating device at the dispatcher's office connected in said circuit, and means controlled by said track relay for changing the resistance of said circuit to cause operation of said translating device. 80
36. A railway traffic controlling system comprising a main track and a connecting track, a power operated switch movement operating the switch to the connecting track, a signal, a track circuit with a track relay, a three position relay selectively controlling said switch movement and said signal, a dispatcher's office with a controlling switch, a circuit connecting said three position relay with said controlling switch for the selective operation of said three position relay, a translating device at the dispatcher's office connected in said circuit and means on the trackway at said connecting track for opening and closing a circuit for operating said translating device, without interfering with the normal operation of said three position relay. 85
37. A railway traffic controlling system comprising a main track and a connecting track, a power operated switch movement operating the switch to the connecting track, a track circuit with a track relay for a portion of the track adjoining the portion where the track switch is located, a control relay selectively controlling said switch movement, a dispatcher's office with a controlling switch, a circuit connecting said control relay with said controlling switch for the selective operation of said switch movement, a translating device connected in circuit, a time recording device operated by said translating device and means for operating said translating device by said track relay. 90
38. A railway traffic controlling system comprising a main track and a connecting track, a power operated switch movement operating the switch to the connecting track, a signal, a track circuit with a track relay, a three position relay selectively controlling said switch movement and said signal, a dispatcher's office with a controlling switch, a circuit connecting said three position relay with said controlling switch for the selective operation of said relay, and a translating device at the dispatcher's office connected in said circuit with a resistance therein connecting said three position relay with said controlling switch for the selective operation of said relay, a translating device in said circuit, and means whereby said resistance is shunted by said track relay in the deenergized position to cause the operation of said translating device. 100
39. A railway traffic controlling system comprising a main track, a power operated switch movement operating the switch to the connecting track, a trackway signal giving a plurality of indications, a track circuit with a track relay, a three position relay selectively controlling said switch movement and the indications of said signal, said track relay controlling part only of 105
- said signal indications, a dispatcher's office with a controlling switch, a circuit connecting said three position relay with said controlling switch for the selective operation of said three position relay, and a translating device at the dispatcher's office connected with said circuit and operated by the presence of a train on the track. 110
40. A railway traffic controlling system comprising a main track and a connecting track, a power operated switch movement operating the switch to the connecting track, a trackway signal, a track circuit with a track relay controlling said switch movement, a three position relay selectively controlling said switch movement and said signal, a dispatcher's office with a controlling switch, a circuit connecting said three position relay with said controlling switch for the selective operation of said three position relay, a translating device at the dispatcher's office connected in said circuit and means on the trackway at said connecting track for opening and closing a circuit for operating said translating device, without interfering with the normal operation of said three position relay. 115
41. A railway traffic controlling system comprising a main track and a connecting track, a power operated switch movement operating the switch to the connecting track, a trackway signal, a control device for controlling said switch movement and said signal, a dispatcher's office with a controlling switch, a circuit connecting said control device with said controlling switch for the operation of said device, a translating device at the dispatcher's office connected in said circuit, and means on the trackway at the connecting track for opening and closing a circuit for operating said translating device without interfering with the normal operation of said control device. 120
42. A railway traffic controlling system comprising a main track and a connecting track, a power operated switch movement operating the switch to the connecting track, a track circuit with a track relay controlling said switch movement, a device having means for selectively establishing a plurality of circuits controlling said switch movement, a dispatcher's office with a controlling switch, a circuit connecting said device with said controlling switch for the selective operation of said device, and a translating device in the dispatcher's office connected in said circuit and means on the trackway operated by the presence of a train for operating said translating device. 125
43. A railway traffic controlling system comprising a main track and a connecting track, a power operated switch movement operating the switch to the connecting track, a track circuit with a track relay controlling said switch movement, an electric apparatus selectively responsive to current of different characteristics controlling said switch movement, a dispatcher's office, current sources of different characteristics, a circuit connecting said apparatus with said dispatcher's office, means in the dispatcher's office for energizing said circuit with current from one of said sources of a particular characteristic for the selective operation of said apparatus, and a translating device connected in said circuit at the dispatcher's office and means on the trackway at the connecting track operated by a train on the track for operating said translating device. 130

PAUL J. SIMMEN
